MEANS FOR WAVING HAIR

John C. E. Butterfield, Toronto, Ontario, Canada

Application August 10, 1950, Serial No. 178,592

4 Claims. (Cl. 132—9)

1

This invention relates to the dressing or treatment of women's hair to give it what is commonly referred to as a "permanent wave." In waving hair, it is usual to treat the hair with a chemical or other material and then form the waves by rolling strands of groups of hair, usually in conjunction with a moist strip of paper, on to rollers or curlers of various kinds, and keeping the hair wound on said rollers or curlers sufficiently long for the chemical or other treating material to have its effect on the hair. In some cases additional chemical or treating material, or heat treatment, is applied to the hair while it is wound on the rollers or curlers.

It is generally quite a difficult task to divide the hair into strands or groups and to arrange the hair in each strand or group in substantial parallelism to facilitate the rolling up of the strands of hair with the paper as a flat strip.

It is the object of the present invention to devise means to facilitate the separation of the hair into separate strands or groups, and to arrange the hair in each strand or group into a substantially flat strip with the individual hairs in approximately parallel relationship, and to provide means for holding the hair in each strand in said flat parallel relationship while it is being wound upon the roller or curler.

This object is attained by the employment of the means hereinafter more fully described and illustrated in the accompanying drawings in which

Fig. 1 is an elevation of a strand assembling tool;

Fig. 2 an end view of the same;

Fig. 3 an elevation of a modified form of strand assembling tool;

Fig. 4 a perspective view of the strand holding and winding means;

Fig. 5 a longitudinal section through the same;

Fig. 6 an end view of the same with the curler spool removed;

Fig. 7 a detail longitudinal section of the strand holding and winding means;

Fig. 8 an elevation of the winding roll of curler; and

Fig. 9 a plan view of the paper wrapping for the end of the hair strand.

In the drawings like numerals of reference indicate corresponding parts in the different figures.

In waving hair, it is usual to form each wave from a strand composed of the hair from an area of the scalp of approximately equal size. Certain hairdressers, for example, make each strand

2

consist of the hair growing in an area approximately $2\frac{1}{2}'' \times 1''$ and the hair of each of said area is arranged to form a flat strip or strand having a width of approximately $1\frac{1}{2}''$. It will be evident, however, that the size of the area from which the hair is formed into a separate strand may be varied to suit special individual requirements.

The feature of the present invention is the provision of means for facilitating the arranging of the hair into a substantially flat strand with the hairs arranged in substantially parallel relationship, and the provision of means for maintaining the hair in the form of a flat strand and facilitate its being wound upon the roller or curler, and at the same time obtain more uniformity in the waves.

The first step in the process is to grasp with one hand the hair growing in a given area of the scalp and arrange it in the form of a flat strand with the individual hairs arranged substantially parallel. This may be conveniently accomplished by means of the comb A shown in Figs. 1 and 2, which comb is provided at one side with a group of diverging teeth 1, which teeth will collect the hair intermediate the outer ends of the two outermost teeth, and, when forced through the hair, will gradually guide the hair within the width of the comb at the inner ends of the teeth. The hair in the narrowed formation is grasped while the comb is removed. If further narrowing is desired, the comb may be used a second time by engaging the intermediate teeth with the hair.

The straight teeth 2 may be used as an ordinary comb or may be used to maintain the hair in the flat strand form.

In Fig. 3 is shown a modified form of tool B for reducing the width of the strand of hair. In this form the teeth 3 act in the same manner as teeth 1 in the tool A of Fig. 1.

A suitable type of curler or roller is shown in Fig. 8, in which a long spool 4 is rotatably mounted on a stem 5, on which stem is hingedly connected a keeper 6, which is provided with a rib 7 adapted to engage with radially arranged teeth 8 on the end of the spool.

To shorten and simplify the work of rolling the strand of hair on to the spool of the curler, a special guide frame is provided. This guide frame comprises a platform 9 provided with an upwardly directed flange 12 at each side. At the forward end of this platform is provided a series of teeth or separators 10. Preferably the platform 9 has its rear portion 9a slightly below

the level of the forward portion, as will be seen in Fig. 5, to form a transverse shoulder 11 on its upper surface.

At each side of the guide frame is mounted a spring arm 14, which is bent to form a loop 14a at the rear end of the platform, and then extends forwardly to a position near the forward end of the side flange 12, as shown in Fig. 4.

This guide frame is used as follows. A binding paper, such as illustrated in plan in Fig. 9, and which has been suitably moistened, is first positioned with its wide end over the depressed portion 9a of the platform with its end butting against the shoulder 11 and with its side portions bent upwardly inside the flanges 12. Now, assuming that the narrow flat strand of hair has been prepared as described above, the strand is then laid over the platform 9 with the teeth 10 projecting between the parts of the strand to maintain the strand in flat form, and with the hair ends lying over the paper binding adjacent the spool 4, which spool is mounted in the loops 14a as indicated in Fig. 4.

The narrow end of the binding paper is then bent forwardly to overlie the hair and the side edges of the under portion bent thereover thus forming a container for the end of the hair strand.

The paper with the end of the hair strand therein is then wound about the spool 4, and as the strand is wound, the spool is rolled forwardly over the platform, being held in place against the upper edges of the flanges 12 by the spring arms 14, as indicated in Fig. 5. As the winding continues, the spool will become disengaged from the spring arms 14 and any additional length of the strand may be wound upon the spool. When winding is complete, the keeper 6 is moved to the position shown in Fig. 8 to prevent unwinding of the strand from the spool.

The same procedure will be followed in waving the strands formed of hair on other portions of the scalp.

The hair is allowed to remain on the curlers until such time as the chemical or other material employed to treat the hair has had the desired effect.

The straight toothed portion 2 of the comb A is of a width to fit between the flanges of the guide frame so the comb may be used to assist in positioning the strand on the platform of the guide frame.

What I claim is:

1. For use in waving hair, a guide frame comprising a platform having a retaining flange at opposite sides thereof, said platform having transversely arranged hair engaging teeth adjacent one end thereof; a pair of longitudinally directed arms secured to the other end of the platform and extending towards the teeth and cooperating with the flanges to form between them spool guides.

10 2. For use in waving hair, a guide frame comprising a platform having a retaining flange at opposite sides thereof, said platform having transversely arranged hair engaging teeth adjacent one end thereof; a pair of longitudinally directed arms secured to the other end of the platform and extending towards the teeth and cooperating with the flanges to form between them spool guides, the surface of the platform at the end remote from the teeth being depressed below the level of the remainder of said surface.

15 3. For use in waving hair, a guide frame comprising a platform having a retaining flange at opposite sides thereof, said platform having transversely arranged hair engaging teeth adjacent one end thereof; a pair of longitudinally directed arms secured to the other end of the platform and extending towards the teeth and cooperating with the flanges to form between them spool guides.

20 4. For use in waving hair, a guide frame comprising a platform having a retaining flange at opposite sides thereof, said platform having transversely arranged hair engaging teeth adjacent one end thereof; a pair of longitudinally directed arms secured to the other end of the platform and extending towards the teeth and cooperating with the flanges to form between them spool guides.

25 5. For use in waving hair, a guide frame comprising a platform having a retaining flange at opposite sides thereof, said platform having transversely arranged hair engaging teeth adjacent one end thereof; a pair of longitudinally directed arms secured to the other end of the platform and extending towards the teeth and cooperating with the flanges to form between them spool guides, said arms being shaped to form a spool-supporting loop at the end of the platform.

JOHN C. E. BUTTERFIELD.
